LIQUID FUSE

Ralph H. Earle, Wauwatosa, Wis., assignor to
Line Material Company, South Milwaukee, Wis.,
a corporation of Delaware

Application November 14, 1932, Serial No. 642,502

12 Claims. (Cl. 200—120)

This invention relates to liquid fuses, and is an improvement over that disclosed in the co-pending application Serial Number 609,453 filed May 5, 1932, for Liquid fuses jointly with Walter E. Mitzelstadt.

In liquid fuses it is the customary practice to provide a tube of glass or other insulating material within which an arc extinguishing liquid is carried. An upper and a lower contact are provided connected by a fuse link and a flexible cable, a spring being employed to draw the lower portion of the fuse downwardly when the fuse blows.

These devices as heretofore made are subject to the defect in that an arc is frequently established and plays about and damages the upper contact, often cracking and breaking the glass.

This invention is designed to provide a liquid fuse which will prevent arcing at the upper contact, which greatly lengthens the path of the arc and introduces a "hairpin" turn in the path of the arc, which protects the glass or insulating tube and the upper contact, and which shoots the products of combustion far away from the fuse contacts, and in which means are provided, as by means of a rupturable diaphragm, for completely sealing the tube in its normal condition, such diaphragm, however, in no way interfering with the above outlined results.

In greater detail further objects are to provide a liquid fuse having a main or stationary insulating tube of glass or other suitable material and a movable insulating tube which may be of fiber or of other insulating material, which is initially housed within the glass tube and is automatically moved upwardly when the fuse blows and projects from the glass tube and from the upper contacts, and which thus substantially instantly elongates the path which an arc would have to follow and at the same time forms a vent which projects the products of combustion far away from the fuse contacts.

This invention is an improvement over that described in the above identified co-pending application, and has for its additional objects the provision of means for positively starting or forcing the fiber or other insulating tube outwardly from the main tube, such tube subsequently being drawn or forced farther outwardly by the gas pressure produced by the arc boiling the liquid, so that there is no possible chance of failure of the device under any condition of fuse rupturing load.

The device is so made that the load for which the device will operate may be suddenly applied

or may be gradually applied, but in all cases the positive operation of the apparatus is assured.

Embodiments of the invention are shown in the accompanying drawings, in which:—

Figure 1 is an elevation of a liquid fuse, with parts broken away and parts in section. 5

Figure 2 is a top view of Figure 1, very much enlarged and with parts broken away.

Figure 3 is a view showing a modified form of the invention. 10

Figure 4 is a view showing a modified form of the invention in which a cap or stopper is employed for initially starting the tube.

Figure 5 is a view showing a further form of the invention, in which means are provided for retracting the slidable tube after it has been ejected. 15

Figure 6 is a sectional view on the line 6—6 of Figure 5.

Referring to the drawings, particularly Figures 1 and 2, it will be seen that the liquid fuse comprises a main tube 1 which may be of glass or other similar material and is adapted to contain an arc extinguishing liquid in the usual manner. This tube is provided with an upper contact 2 and a lower contact 3. Within the tube a fuse link 4 is provided adjacent its upper end and is carried by a supporting spring bridge 5, as indicated in Figures 1 and 2. 20

It is preferable to form this fuse link so that there are two ribbons indicated at 6 at its upper end which are looped around the curved feet of the spring bridge 5, as shown in Figure 1, and are clamped between such curved feet and the bottom of notches or slots 7 within which the ends of this togglelike spring bridge 5 are seated. If desired, a cork 8 may cover the reduced portion of the fuse link. 25

The lower end of the fuse link is connected with the lower contact 3 by means of a flexible cable 9, a coiled spring 10 being also attached to the lower end of the fuse link for drawing the lower portion of the fuse link downwardly after the fuse has blown. 30

The upper contact 2 comprises a clamping ring 45 or nut 11 which is screw threaded to the upper end of the upper contact and clamps a rupturable diaphragm 12 formed of thin, relatively soft, metal or alloy so as to seal the device and prevent evaporation or loss of the arc extinguishing liquid. 50

A stop ring 13 is clamped beneath the diaphragm 12 by the nut 11 and is provided with a central opening 14, see Figure 2, through which the fuse parts may pass. It is also provided with notches 15 through which the feet of the bridge 55

member 5 may pass when the parts are blown outwardly from the fuse.

This stop ring may be formed of any suitable material. It may be formed of steel, sheet steel or sheet brass, or if made of sufficient thickness, it obviously may be formed of insulating material, although there is a considerable blow struck against this stop ring, as will appear as the description of the invention proceeds.

10 A slidable tube 16 fits loosely within the glass tube 1 and extends downwardly around the fuse link and a considerable distance below the fuse link. It is provided with a reduced upper portion 16' and a shoulder 17 is formed between the reduced upper portion and the lower portion. This shoulder is adapted to engage the stop ring 13 and to thereby arrest the outward motion of the slidable insulating tube 16.

15 The tube 16 is urged outwardly by means of a compression spring 19 which is of larger diameter than the spring 10. The spring 19 is lighter than the spring 10.

20 Under normal conditions when the fuse is intact, the parts are in the positions shown in Figure 1. When the fuse blows, the diaphragm 12 is ruptured and blown outwardly and the pressure of the bridge 5 or suspension member for the fuse link against the upper end of the slidable tube 16 is removed.

25 30 The spring 19 operates to project the tube 16 outwardly in a positive mechanical manner. The gas pressure generated by the arc boiling the liquid produces a pressure upon the lower edge of the tube which is not balanced by the atmospheric pressure on the upper edge of the tube and this pressure, together with the frictional drag produced by the outwardly rushing gases, force the tube outwardly and complete its outward motion until the shoulder 17 strikes against the stop ring 13. The bridge piece 5 and such remaining portions of the upper end of the fuse link are blown outwardly and are freely detached from the slid- able tube.

35 40 Suppose that a very small load although sufficient to rupture the fuse is gradually applied. Obviously there would not be as violent an evolution of gases as if a dead short-circuit had occurred. Nevertheless, this device will function equally well under these conditions for the initial movement of the slidable tube is mechanically imparted thereto and is not dependent upon the outwardly rushing gases. After the tube has been started outwardly, the gas pressure and the outwardly rushing gases complete the outward motion of the slidable tube.

45 50 In the form of the invention shown in Figure 3 the fiber tube 20 is substantially similar to the fiber tube 16 previously described, except that it is provided with a bead or flange 21 about its upper end beneath which the feet of the bridge member 5 hook when the parts are in their normal position.

55 60 The rupturable diaphragm 12 is held in place by the clamping nut 11, as previously described, but it is preferable to provide a split stop ring or two-part stop ring 22 in the form shown in Figure 3. This stop ring is itself provided with notches or slots 23 within which the feet of the bridge member 5 seat. It is provided with an 65 inwardly projecting flange 24 which is adapted to engage the shoulder 25 formed on the fiber tube to arrest its outward motion at the extreme upper limit of its outward stroke.

70 75 This invention also provides means whereby a mechanical pull is imparted to the slidable

tube. To initiate its motion when the fuse blows, this mechanical pull or outward pushing movement is imparted to the tube due to the fact that the bridge member 5 hooks beneath the upper flange 21 of the slidable tube and as the upper part of the fuse, the bridge member and the cork 8 are blown outwardly, it is obvious that this bridge member suddenly draws the tube outwardly and thereby mechanically initiates its outward motion. The outward motion of the 10 slidable tube is completed as previously described.

15 In the form of the invention shown in Figure 4, the slidable fiber tube 26 is free from any shoulder or flange at its upper end. It is, however, provided with a shoulder 27 corresponding to the shoulders 17 and 25 previously described. This form of the invention has been illustrated as providing a tapered shoulder 27 and a correspondingly tapered portion 28 formed on the stop ring 29, although this form or the flat shoulder 20 may be used on any of the several forms of the invention. The tapered shoulder, however, acts somewhat as a cushion and arrests the motion of the tube in a more gradual manner than the abrupt shoulder previously described. There 25 seems to be a slight cushioning action in the actual operation of the device. However, in this form of the invention the stop ring 29 is screwed into the upper contact 30 carried at the upper end of the main tube 1.

30 35 A closure cap 31 is provided and is equipped with a tapered stopper-like portion 32 which fits into the tapered upper end of the tube 26, as shown, and thus holds the tube 26 in place, and in addition closes the open upper end of the 35 upper contact 30.

40 45 It is to be noted from Figure 4 that the fuse link 33 is attached to the stopper or central portion 32 of the cap. The lower end of the fuse link is drawn downwardly by the spring 10 and consequently the cap 31 is held tightly in place.

50 55 It is preferable to provide a knife edge 34 at the upper end of the contact 30, as shown in Figure 4, so that this knife edge bears against or seats against the underside of the cap 31. A 45 tight seal is thus secured due to the fact that the cap is drawn downwardly by the spring 10 and consequently the knife edge insures a secure airtight and liquid-tight seal or joint between the upper contact 30 and the cap 31.

60 65 When the fuse blows, the cap 31 is released and is blown upwardly away from the device. This cap draws the fiber tube 26 along with it until the shoulder 27 engages the shouldered portion 28. The cap 31 is then blown from the 55 fiber tube.

70 75 In this form of the invention the fiber tube or slidable tube is also mechanically started outwardly by mechanical means and its outward motion may be completed as previously described. 60 Also the cap 31 performs the double purpose of a means for moving the slidable tube outwardly and also as a means for sealing the main fuse tube at the upper end of the upper contact. It is also preferable in this form of the invention 65 to provide the cap 31 with an annular, downwardly projecting flange 35 which fits over the adjacent upwardly projecting portion of the upper contact 30.

80 85 In the form of the invention shown in Figure 5 a relatively shorter insulating tube or sliding tube 36 is provided. This sliding tube is provided with a stop shoulder 37 which may be tapered and which engages the tapered shoulder 38 formed on the lower side of the stop ring 75

39. This stop ring is provided with slots or notches 40 which receive the ends or feet of the bridge member 41, such bridge member supporting the upper end of the fuse link 42, as previously described. A rupturable diaphragm 43 closes the fuse structure as previously described.

10 The ends of the bridge member or suspension member 41 hook within an annular groove 44 formed externally of the upper portion of the fiber tube 36.

15 The sliding tube or fiber tube 36 is provided with a bottom shoulder or flange 45 for a purpose hereinafter to appear.

20 A disk 46 is attached to the upper end of the spring 10 in any suitable manner. For example, the fitting 47 may pass through the disk 46, and due to the fact that an attaching screw 48 joins such fitting to the lower end of the link, it is apparent that the fitting 47 or connector cannot be drawn downwardly through the disk. However, the disk 46 normally stands in about the position shown in Figure 5 intermediate 25 the ends of the slidable tube 36. It is preferable to form the disk 46 with a plurality of openings 49 or it may be formed in any other manner to provide a spider-like structure or open structure so that the arc extinguishing liquid will not act to prevent the free sliding motion of the disk in a manner hereinafter to appear.

25 When the fuse blows, the bridge member 41 and whatever remains of the upper portion of the fuse link, with the cork 8 are blown outwardly through the then ruptured diaphragm 43. Inasmuch as the ends of the bridge member or suspension member 41 are hooked into the groove 44 in the slidable tube, it is apparent that this slidable tube is suddenly mechanically started outwardly and its outward motion is thereafter completed in the manner previously described. This action is very fast, indeed, and outruns the action of the spring 10. However, an instant later the spring 10 contracts and the stop or disk 46 is drawn downwardly into engagement with the lower shoulder 45. The slidable tube is thus drawn downwardly back into the device by means of the spring 10 and it will keep on downwardly to the lower end of the glass tube 1, sinking within the arc extinguishing liquid.

30 The tube 36 or in fact any of the slidable tubes disclosed may be formed of any suitable insulating material, preferably of fiber. They may, however, be formed of other material, such, for instance, as glass, if desired, to prevent obscuring the vision of an inspector when examining the device. If they are formed of glass, it is obvious that the stop rings would then be formed of somewhat yielding material, such as fiber, "bakelite", or other suitable material.

35 In addition to this, it is within the scope of this invention to form the lower portion of any of the slidable insulating tubes of glass and the upper portion of other material. Also if it is desired, the lower end of the tube shown in Figure 5 may be weighted, although this has not been found necessary in the actual tests of the device.

40 In the form of the invention shown in Figure 5, the slidable tube slides downwardly completely away from the upper contact. However, in all forms of the invention the sliding tube is first mechanically started outwardly by mechanical means so that it has a positive initial outward motion. Thereafter the fuse suspension means

in whatever form it may take is disengaged from the slidable tube and the subsequent completion of the outward motion of the slidable tube is accomplished by the outwardly rushing gases.

45 In actual tests of this invention it has been found that a positive assured action of the fuse occurs under all conditions. The fuse always clears and the slidable tube is always positively pulled outwardly by mechanical means at the initiation of its outward motion. Also the outwardly travelling tube directs the gases or vapors and the discharged liquid far away from the upper contact.

50 The slidable tube being projected outwardly at the time of the blowing of the fuse forms a "hairpin" turn in the arc as the tube moves outwardly, and forces the arc to pass through the bore of the tube and thereafter over to the upper contact even at the early portion of its outward motion. Thus the path of the arc 20 is greatly lengthened and the arc is quickly snapped out and a very sharp bend is formed therein.

55 It is impossible for an arc to strike from the spring lug to the inner portion of the contact 30, because the portion of the tube lying below the shoulder 27 covers the contact 30 at the time the shoulder 27 has contacted with the shoulder 28. The same action occurs in all forms of the invention.

60 It will be seen further that all forms of the device may be simply constructed and are relatively inexpensive to manufacture.

65 Although this invention has been described in considerable detail, it is to be understood that such description is intended as illustrative rather than limiting, as the invention may be variously embodied and is to be interpreted as claimed.

I claim:

1. A liquid fuse comprising an insulating tube 40 adapted to contain an arc extinguishing liquid and having upper and lower contacts, said upper contact having an open central portion, a rupturable diaphragm closing the opening through said upper contact, a fuse link electrically connected to said contacts, a sliding tube located within said main tube adapted to be projected outwardly upon rupturing of said fuse link, and means detachably interlocking with said sliding tube for mechanically initiating the outward motion of said sliding tube when said fuse blows.

2. A liquid fuse comprising an insulating tube adapted to contain an arc extinguishing liquid and having upper and lower contacts, said upper contact having an open central portion, a rupturable diaphragm closing the opening through said upper contact, a fuse link electrically connected to said contacts, a sliding tube located within said main tube adapted to be projected outwardly upon rupturing of said fuse link, and means for mechanically initiating the outward motion of said sliding tube when said fuse blows, said means temporarily holding said sliding tube in place.

3. A liquid fuse comprising an insulating tube adapted to contain an arc extinguishing liquid and having upper and lower contacts, said upper contact having an open central portion, a rupturable diaphragm closing the opening through said upper contact, a fuse link electrically connected to said contacts, a sliding tube located within said main tube adapted to be projected outwardly upon rupturing of said fuse link, and means for mechanically initiating the outward motion of said sliding tube when said fuse blows,

said means controlled by said fuse link and temporarily holding said sliding tube in place.

4. A liquid fuse comprising an insulating tube adapted to contain an arc extinguishing liquid and having upper and lower contacts, a fuse link electrically connecting said contacts, suspension means for said fuse link adjacent said upper contact, a tension spring drawing downwardly upon said fuse link, and a slidable tube located within said main tube normally extending from adjacent the upper end of said insulating tube to a point a material distance below the lower edge of said upper contact and extending over a portion of said tension spring and adapted to be projected outwardly when said fuse link blows, said suspension means being blown outwardly when said fuse blows, said suspension means and said slidable tube being mechanically connected, whereby when said fuse blows said suspension means initiates the outward motion of said slid- 10 able tube, the generated gases completing the outward travel of said slidable tube.

5. A liquid fuse comprising an insulating main tube adapted to contain an arc extinguishing liquid and having upper and lower contacts, the upper contact having an open central portion, a rupturable diaphragm normally closing the open central portion of said upper contact, a fuse link electrically connecting said contacts and located within said tube, a tension spring located within said tube and attached to the lower portion of said fuse link, a suspension member for said fuse link supported from said upper contact, and a slidable tube surrounding said fuse link and adapted to be projected outwardly through said upper contact when said fuse link blows, said slidable tube being connected to said suspension means and being located below said diaphragm, said slidable tube having a shoulder thereon and said main tube having means for engaging said shoulder to prevent complete expulsion of said slidable tube when said fuse blows.

6. A liquid fuse comprising an insulating tube adapted to contain an arc extinguishing liquid and having upper and lower contacts, the upper contact having an open central portion, a rupturable diaphragm normally closing the open central portion of said upper contact, a fuse link electrically connecting said contacts and located within said tube, a tension spring located within said tube and attached to the lower portion of said fuse link, a suspension member for said fuse link supported from said upper contact, and a slidable tube surrounding said fuse link and adapted to be projected outwardly through said upper contact when said fuse link blows, said slidable tube being connected to said suspension means and being located below said diaphragm and below said suspension means.

- 60 7. A liquid fuse comprising a main tube of insulating material adapted to contain an arc extinguishing liquid and having upper and lower contacts, a fuse link electrically connecting said contacts, a tension spring drawing downwardly upon said fuse link, a slidable tube surrounding said fuse link and adapted to project outwardly from said main tube, said slidable tube extending downwardly from adjacent the upper end of said main tube to a point a material distance below said upper contact and surrounding a portion of said spring, and a suspension member for said fuse link supported from said upper contact, said suspension member and said slidable tube having interengaging portions.

- 75 8. A liquid fuse comprising a main tube of insu-

lating material adapted to contain an arc extinguishing liquid and having upper and lower contacts, a fuse link electrically connecting said contacts, a slidable tube surrounding said fuse link and adapted to project outwardly from said main tube, a suspension member for said fuse link supported from said upper contact, said suspension member and said slidable tube having detachable, interlocking portions, and means for arresting the outward motion of said slidable tube at a predetermined point, said means being carried jointly by said main tube and said slid- 10 able tube.

9. A liquid fuse comprising a main tube of insulating material adapted to contain an arc extinguishing liquid and having upper and lower contacts, a fuse link electrically connecting said contacts, a slidable tube surrounding said fuse link and adapted to project outwardly from said main tube, a suspension member for said fuse link supported from said upper contact, said suspension member and said slidable tube having interengaging portions, and means carried directly by said main tube and said slidable tube for arresting the outward motion of said slidable tube at a predetermined point, said interengag- 15 able portions of said slidable tube and said suspension member being detachable when said slidable tube is at its outermost position, whereby said suspension member may be blown from said 20 slidable tube at the limit of motion of said slid- 25 able tube.

10. A liquid fuse comprising a main tube of insulating material adapted to contain an arc extinguishing liquid and having a lower contact 35 and an annular upper contact, a rupturable dia- phragm normally closing said upper contact, a suspension member supported from said upper contact, a fuse link extending downwardly from said suspension member and electrically connected to said contacts, a spring drawing down- 40 wardly upon the lower end of said fuse link, said suspension member being in the form of a toggle with inwardly turned ends, and a slidable tube surrounding said fuse link and interlocked 45 with the inturned ends of said suspension member, whereby when said fuse link blows said diaphragm is blown outwardly and said suspen- sion member is blown outwardly through said annular upper contact, thereby drawing said 50 slidable tube outwardly.

11. A liquid fuse comprising a main tube of insulating material adapted to contain an arc extinguishing liquid and having a lower contact and an annular upper contact, a rupturable dia- 55 phragm normally closing said upper contact, a suspension member supported from said upper contact, a fuse link extending downwardly from said suspension member and electrically connected to said contacts, a spring drawing down- 60 wardly upon the lower end of said fuse link, said suspension member being in the form of a toggle with inwardly turned ends, a cork surround- 65 ing said fuse link and located below said suspen- sion member, and a slidable tube surrounding said fuse link and interlocked with the inturned ends of said suspension member, whereby when said fuse link blows said diaphragm is blown outwardly and said suspension member is blown outwardly through said annular upper contact, thereby drawing said slidable tube outwardly.

12. A liquid fuse comprising a main tube of insulating material adapted to contain an arc extinguishing liquid and having a lower contact and an annular upper contact, a slidable tube 75

adapted to slide outwardly through said upper contact when said fuse blows, a suspension member supported from said upper contact and engaging said slidable tube, a fuse link carried by said suspension member and projecting downwardly therefrom, a tension spring for drawing downwardly upon the lower end of said fuse

link, and means for establishing an operative connection between said spring and said slidable tube after said slidable tube has been projected outwardly, whereby said slidable tube is subsequently retracted and drawn downwardly into said main tube.

5

RALPH H. EARLE.
